UNITED STATES PATENT OFFICE.

GEORGE ADAM KAHL, OF PLAINSEBERG, CALIFORNIA.

BUILDING-BLOCKS.

960,948.

Specification of Letters Patent. Patented June 7, 1910.

Application filed April 19, 1907. Serial No. 369,127.

To all whom it may concern:

Be it known that I, GEORGE ADAM KAHL, a citizen of the United States, residing at Plainsberg, in the county of Merced and State of California, have invented new and useful Building-Blocks; and I do hereby declare the following to be a full, clear, and exact description of the invention, such as will enable others skilled in the art to which it appertains to make and use the same.

The invention relates to building blocks, and particularly those composed of cement, stone or the like, and has for its object to provide means for constructing a building which can be securely built, and which will be capable of withstanding earthquake shocks without being demolished.

With these and other objects in view, the invention consists in the novel construction and arrangement of parts hereinafter described and shown and particularly pointed out in the appended claims.

In the drawings:—Figure 1 is a perspective view of the corner of a building constructed in accordance with this invention. Fig. 2 is a perspective view of the blocks. Fig. 3 is a plan view of the lower face of block 2.

Referring to the drawings, 1 and 2 designate the two styles of blocks embodied in my invention. The block 1 is provided with a groove 3 on the under side and a rib 4 on the upper face thereof, each of which extends the entire length of the block.

The block 2 is provided with a transverse rib 6, which extends across the end thereof, and a longitudinal rib 7, which extends one half the length of said block. Between the inner end of the rib 7 and the transverse rib 6 is a space equal to one half the width of the block. The under side of the block 2 is provided with a transverse groove 5, and a longitudinal groove 8 corresponding in size

to the ribs 6 and 7 on the opposite face of the block.

In constructing the wall of a building, a corner is formed by registering the groove 3 with the rib 6, as clearly shown in Fig. 1 of the drawings.

Having thus described my invention, what is claimed is:

1. In a structure composed of a series of building blocks, disposed in break joint order, a block having on one side a centrally disposed longitudinal rib, and on its other side a centrally disposed longitudinal groove, the rib and groove extending the entire length of the block and a second block having on one side adjacent to one end a transverse rib, and on the same side a centrally disposed longitudinal rib that terminates short of the transverse rib a distance equal to one half the width of the first block, the second block being provided on the side opposite that carrying the transverse rib with a transverse groove arranged directly opposite the transverse rib, and a centrally disposed longitudinal groove opposite the centrally disposed longitudinal rib that terminates short of the transverse groove.

2. A building block having on one side adjacent to one end a transverse rib, and on the same side a centrally disposed longitudinal rib that terminates short of the transverse rib a distance equal to one half the width of said block, said block being provided with grooves on its opposite face, corresponding to each of said ribs.

In testimony whereof I have signed my name to this specification in the presence of two subscribing witnesses.

GEORGE ADAM KAHL.
